UNITED STATES PATENT OFFICE

2,443,380

TRACK SANDING APPARATUS FOR STEAM LOCOMOTIVES AND OTHER POWER-PROPELLED VEHICLES

Wilson Downs, Shildon, England

Application April 28, 1945, Serial No. 590,794
In Great Britain February 23, 1944Section 1, Public Law 690, August 8, 1946
Patent expires February 23, 1964

4 Claims. (Cl. 291—3)

1

This invention relates to track sanding apparatus for steam locomotives and other power-propelled vehicles, and has for its object to provide an improved construction.

Further and favourable objects will appear from the following description.

Track sanding apparatus in accordance with the present invention is of the kind wherein a jet of steam, compressed air or other fluid under pressure in the lower portion of a sand pipe depending from a sand box on the locomotive or the like ejects sand onto the track, and is characterised in that the sand in the box, is, by the suction of the jet, drawn up into a pipe within said box through a slot or slots in the underface of said pipe which is connected to the upper end of the sand pipe and a heated surface located adjacent the slotted pipe for drying the sand passing thereto.

Where steam or other heated gaseous fluid is employed, advantage is also taken of the heat available to dry the sand adjacent to the slotted pipe which forms the suction tunnel in the sand box, in order to facilitate the feeding of the sand to the sand pipe and its distribution on to the track.

As applied to a steam locomotive, the pipe supplying steam to the jet in the lower portion of the sand pipe is preferably associated with the slot in the underface of the pipe in the sand box, in which case heat from the steam pipe will dry the sand adjacent to said slot and ensure an immediate supply of dry sand to the sand pipe. The pipe in the sand box may be coiled, and the slot in its under face may be continuous or interrupted at intervals.

In the compressed air operated form of device, it may be considered desirable to dispense with one of the combination of pipes in the sand box and to attach the air pipe connection directly to the jet near the outlet of the sand pipe.

According to one construction adapted for the use of steam, the sand box has inwardly-sloping sides and is mounted as usual on the running board or equivalent member of the locomotive or the like. At the bottom, the box is closed by a fitting having two apertures connected respectively to the upper end of the sand pipe and to a steam pipe leading to the jet in the lower portion thereof. In the box a coiled pipe is provided having a substantially continuous narrow slot in its underface, and adjacent to said slot there is arranged a steam pipe connected at its upper end to a supply of steam and at its lower end through the fitting at the bottom of the box

2

to the pipe connected to the jet. The steam pipe runs parallel with the underface of the coiled pipe in the box and is disposed at such distance therefrom that its provides long narrow apertures on each side of the slot in said underface.

The steam jet is provided within a fitting mounted near the lower end of the sand pipe, such jet being concentric with the short straight terminal portion of the sand pipe beyond said fitting which is directed on to the track so that said jet has an unobstructed outlet and distributes the sand on to the track.

The invention will be further described with reference to the accompanying drawings where this construction of improved sanding device for a steam locomotive is illustrated by way of example and wherein—

Fig. 1 is a vertical section of the sandbox and Fig. 2 is a detail view to a larger scale of the associated coiled steam pipe and slotted pipe within the box.

Referring now to the drawings, the sandbox generally designated 1 has a cylindrical portion 2 depending from an open top flanged at 3 and secured to the running board 4 of the locomotive, which running board is apertured so that the box may be charged with sand in any conventional or appropriate manner.

Below the cylindrical portion 2, the sandbox 30 is formed with convergent or inwardly sloping side walls 5 and at the bottom it is closed by a plate fitting 6 having two glands or unions 7 and 8 shown connected respectively to the upper ends of the sand pipe 9 and of a steam pipe 10 terminating in a jet which may be of any known or appropriate form within a distributor fitting 11 carried by the sand pipe.

Within the box 1 a coiled pipe 12 is provided having an air inlet 13 through the cylindrical 40 side wall 2 of the box at its top end and a substantially continuous narrow slot 14 on its underface while adjacent to this slot a correspondingly coiled steam pipe 15 runs, being connected through a union 16 at its upper end and through 45 an appropriate control valve (not shown) to a supply of steam and at its lower end through the union 8 to the steam pipe 10 depending from the sandbox to the distributor 11 wherein is the jet. The coiled portion 15 of the steam pipe runs 50 parallel with the underface of the coiled pipe 12 within the box 1 and is disposed at such a distance from the coiled pipe that long narrow apertures are formed between the pipes on each side of the slots 14.

55 The enlarged detailed view represented in Fig.

2 shows one convenient way of arranging the pipes to attain this end, the coiled pipe 12 being formed with bridges 17 at regular intervals along the slot 14 in its under face, and the coiled portion 15 of the steam pipe being secured to it by clips so that as will be appreciated owing to the steam pipe being held in abutment with the bridges 17 by the clips, it is uniformly spaced therefrom over the whole length of the adjoining coiled portions.

Within the distributor 11 the jet (not shown) of the steam pipe 10 opens into a straight terminal portion 19 of the sand pipe which is directed on to the track so that the jet has an unobstructed outlet and distributes the sand thereon.

In operation, when the steam valve is opened, the suction caused by the jet is effective to draw the sand up into the coiled pipe 12 from the sandbox 1 through the slot 14 in the under face of the pipe and to pass the sand through said pipe into the sand pipe 9 to the lower terminal portion 19 thereof where it is ejected on to the track by the jet. Heat from the steam passing along inside the coiled portion 15 of the steam pipe dries the sand in the vicinity of the pipe, that is immediately adjacent to the slot 14 in the coiled pipe 12, and there is thus ensured a ready supply of dry sand and under all conditions of use while the sand cannot pass from the sandbox 1 to the sand pipe except when the steam valve is open and the jet in operation.

As applied to a locomotive, sand boxes as above described are placed to supply sand in front of and behind the driving wheels, the steam connections to the jets of the sand boxes for foreway and for backway sanding being separately controlled from the cab so that steam can be allowed to pass simultaneously to the jets of either set as may be required, the sand being forcibly projected by the steam under the wheels, thus producing the maximum effect.

While primarily intended for steam locomotives, the improved sand box is applicable to rail coaches and other steam-propelled vehicles, and may also be applied to electric locomotives and trains, and to other vehicles where a supply of

compressed air or other fluid under pressure is available.

What I claim is:

1. Track sanding apparatus of the kind wherein a jet of gaseous fluid under pressure in the lower portion of a sand pipe depending from a sandbox on the vehicle ejects sand on to the track, characterised by the provision in the sandbox of a slotted pipe connected to the sand pipe, into which slotted pipe sand is drawn by the suction of the jet, and a heated surface located in proximity to the slotted pipe for drying the sand passing thereto.

2. Track sanding apparatus comprising a sandbox, a sand pipe terminating in a distributor and a steam pipe terminating in a jet, both depending from said box, and a double coiled pipe arrangement in said box comprising a coiled connecting pipe between the steam pipe and its supply, and superposed on such connecting pipe, an air pipe slotted on its underside for the passage of dry sand to the sand pipe when the jet is operative.

3. Track sanding apparatus according to the preceding claim 2 wherein the coiled connecting pipe is located immediately subjacent to the slot in the underface of the air pipe leaving narrow apertures on each side for the passage into the air pipe of sand dried by heat from the connecting pipe.

4. Track sanding apparatus according to the preceding claim 2 wherein the slotted pipe is provided with bridges across the slot forming abutments against which the connecting pipe is positioned, for instance by means of pipe clips encircling the parallel pipes.
